Atty.

UNITED STATES PATENT OFFICE.

WILLIAM S. FEINBERG, OF CHICAGO, ILLINOIS.

BREATHING APPARATUS FOR SWIMMERS.

Application filed November 15, 1920. Serial No. 424,249.

To all whom it may concern:

Be it known that I, WILLIAM S. FEINBERG, a citizen of the United States, residing at Chicago, in the county of Cook and State of Illinois, have invented a certain new and useful Improvement in Breathing Apparatus for Swimmers, of which the following is a full, clear, concise, and exact description, reference being had to the accompanying drawings, forming a part of this specification.

The invention relates to breathing apparatus, and primarily to that type of these devices which may be utilized by swimmers or 15 in teaching a person to swim.

The invention has among its various objects the provision of a device of this character which will permit the user to submerge the head while swimming and to breathe 20 freely while his head is thus positioned, without fear of being choked by water taken into the lungs through either the mouth or nostrils. This gives confidence to the user and assists him to more aptly learn to swim, and 25 at the same time permits him to practice breathing, so that this function will occur at the proper time with relation to the stroke, which is essential. Thus the user is taught when and how to breathe so that when he 30 has learned to swim and is able to discard the device, his breathing while swimming will be more naturally accomplished.

To accomplish the above referred to advantages the member having the mouth piece 35 is also provided with means for controlling the nostrils. From this mouth piece a tube leads which may be provided with a float to keep the end of the tube remote from the member having the mouthpiece above the 40 surface of the water and afford a communication with the atmosphere.

The device is also provided with means for removably attaching the same to the head of the user so that it cannot become 45 accidentally disconnected and removed from the mouth of the person employing it.

The invention will be more readily understood when read in conjunction with the accompanying drawings, in which—

50 Fig. 1 is a view of a person in the act of swimming and employing the device; and

Figs. 2 and 3 are perspective views of modified structures which may be resorted to for controlling the breathing of the user.

55 The device illustrated in the drawings contemplates the use of the member 10, the

tubular passage 11 which is connected to the member 10 and communicates with the mouthpiece 12. This tubular passage extends above the surface of the water and 60 communicates with the atmosphere, and may be provided with a float 13 to insure keeping this end of the tube above the surface of the water. A head gear 14 is connected to the tube and is provided to prevent the 65 accidental removal of the mouthpiece from the mouth of the user.

The mouthpiece 12 is composed of rubber and is provided with the elongated flange 15 which is inserted into the mouth 70 between the gums and lips of the mouth. A pair of projections 16—16 project inwardly from this flanged portion and are provided so that these portions may be inserted and held between the teeth. This flange 15 is 75 spaced from the body of the member 10 so as to provide a space for the lips between it and the elongated flange 15. The member 10 is also provided with means for controlling the nostrils. One structure which may 80 be employed prevents the person from breathing through the nose when the device is employed, and the other permits breathing therethrough by virtue of the fact that a communication is afforded with the tubular passage. The tubular passage 11 extends from the mouthpiece and communicates with the aperture 18 thereof. The end of the passage remote from the mouthpiece 85

extends above the surface of the water and 90 communicates with the atmosphere, so that the user may breathe through the passage and the aperture 18. The uppermost end of this tubular passage may be provided with the float 13 which keeps this end above the 95 surface of the water and in communication with the atmosphere. The head gear 14 is attached at 19 to the tube leading from the mouthpiece and includes the portion 20

which surrounds the head at about the forehead and also includes the transverse element 21 which extends across the head. This latter device or head gear insures against the accidental removal of the device 10 from the mouth of the user. The tube 11 and other portions may be constructed of rubber or any other suitable material. This tube 11 may also be composed of sections 11

which are connected by means of the connecting portion 22, which may be a metallic tube the opposite ends of which are inserted into the ends of the tube or passage 11.

This structure may be resorted to in permitting the length of the tube to be adjusted so as to compensate for various depths at which the person is swimming below the surface of the water.

The member 10 is, as above referred to, capable of either having a structure which prevents breathing through the nostrils or provided with a structure which permits the person to breathe in this manner. When the former structure is resorted to the member 10 may be provided with the elements 23 which resiliently engage the sides of the nose, close the nostrils and prevent the person from breathing therethrough. In the event that the latter structure is desired, then the member 10 will have the tubular extensions 24-24 extending therefrom, which are designed to be inserted into the nostrils. These extensions communicate with the passages 25 which terminate in a connection with the tubular passage 11. The device may be constructed of rubber or any other suitable material.

However I do not wish to limit myself to the use of this or any other material, nor the

precise construction shown in the drawings, as the invention is susceptible of various structures and modifications.

What I claim and desire to cover by Letters Patent is:

In a device of the class described, the combination of a head piece, having a portion which is adapted to surround the head and a portion which is arranged transversely thereto, a tubular member secured to said portions of said head piece, a mouth piece provided at one end of said tubular member, a tubular section telescopically arranged with respect to the opposite end of the tubular member, another tubular member connected with said tubular section, said last mentioned tubular member having an enlarged chambered portion, said last mentioned chambered portion having a communication with the atmosphere whereby air may enter the chambered portion and pass through all of said tubular portions and thence to the mouth piece.

In witness whereof, I hereunto subscribe my name.

WILLIAM S. FEINBERG.
